UNITED STATES PATENT OFFICE.

HOWARD M. DUDLEY, OF PHILADELPHIA, PENNSYLVANIA

APPARATUS FOR DYEING, SCOURING, OR OTHERWISE TREATING YARN OR OTHER FIBERS IN THE HANK OR SKEIN.

Application filed August 7, 1922. Serial No. 580,301.

To all whom it may concern:

Be it known that I, HOWARD M. DUDLEY, a citizen of the United States, and a resident of Philadelphia, Pennsylvania, have invented certain new and useful Improvements in Apparatus for Dyeing, Scouring, or Otherwise Treating Yarn or Other Fibers in the Hank or Skein, of which the following is a specification.

- 10 My present invention relates more particularly to that type of dyeing or treating machines in which the hanks or skeins of yarn or other fibers, are carried by reels, which reels are arranged to be rotated in a
15 body of liquid disposed within a vat or tank, and in which provision may also be made for imparting independent movement to the hanks or skeins of yarn or other fibers carried by the reel.

20 One object of my present invention is to provide a structure of this type with simple and efficient means whereby the reel, together with the hanks or skeins of yarn supported thereby, may be raised and lowered within the tank or vat.

25

A further object of my invention is the provision of means whereby the reel may be rotated, in either direction, within the dye or treating liquid in the tank, or at any

- 30 stage during the lifting operation; the lifting mechanism being of such a character that the reel may be supported for rotation at the upper or lower limits of travel and at any point intermediate the same.

A further object of my invention is to provide a special form of sliding bearing in which the reel shaft may be journaled.

- 40 A further object of my invention is to provide means for raising and lowering the reel within the tank that will insure easy and uniform movement of the same during its vertical movement within the tank, and a still further object of my invention is to provide ball bearings for the reel and for the shaft passing through the same and forming part of the lifting mechanism.

These and other features of my invention are more fully described hereinafter; reference being had to the accompanying drawings, in which:

Figure 1, is a sectional elevation of one form of vat or tank containing a reel for supporting the skeins or hanks of yarn or other fibers to be dyed or otherwise treated;

showing also mechanism for rotating the reel and for raising and lowering the same, within the scope of my invention. 55

Fig. 2, is an end elevation of the structure shown in Fig. 1, illustrating the reel operating mechanism forming the subject of my present invention.

Fig. 3, is a plan view, partly in section on the line III—III, Fig. 1.

Fig. 4, is a sectional view on the line IV—IV, Fig. 1, illustrating another detail 65 of my invention.

Fig. 5, is a sectional view on the line V—V, Fig. 1, and

Fig. 6, is a sectional view illustrating a modified detail within the scope of my invention. 70

In the drawings, I have illustrated a suitable form of tank or vat for dyeing or treating liquid, which may comprise side walls 1, end walls 2, a bottom 3, and a top or cover 4. Within the tank or vat, a reel for receiving the hanks or skeins of yarn or other fibers, indicated at X, is disposed, which reel may comprise end spiders 5 and 6, each having a trunnion indicated at 7 and 8, and a central spider 9, connected to and spaced from the end spiders 5 and 6, by a series of tie bars 10. 75 80

Between the several spiders, suitable supporting sticks for the hanks or skeins are placed, as indicated at 11 and 12; the sticks 85
11 being polygonal and being rotatably mounted in the several spiders in any usual or well known manner in order that movement may be imparted to the skeins or hanks 90
of yarn or other fibers to avoid the danger of stick marks.

The side walls 1, of the tank or vat are slotted at 15, for the passage of sliding brackets 16 and 17, receiving the trunnions 7 and 8; the vertically disposed portions 16^a and 17^a of said brackets being preferably grooved at their sides as indicated at 18, and adapted to V-shaped slideways 19, carried by the side walls 1 of the vat or tank, and forming the walls of said slots 15. The trunnions are journaled in the sliding brackets 16 and I may provide the ball bearings 20, shown in Figs. 1 and 3, or the plain bearings 20^a, shown in Fig. 6. 100 105 110

For the purpose of rotating the reel within the vat or tank, I may provide one of the trunnions, that indicated at 8, for in-

stance, for operative engagement with a helical gear wheel 21, meshing with a helical gear wheel 22, supported by the sliding brackets 17, which gear wheel 22 may be 5 slidably mounted on a vertical shaft 23; being splined thereto, and said shaft 23 may be driven in either direction.

The shaft 23, carries a pair of bevel pinions 24 and 25, loose thereon, arranged 10 for alternate operative engagement with a bevel gear wheel 26, carried by a driven shaft 27, to which motion may be imparted by means of a belt 28, passing over a pulley 29. A suitable clutch member 30, operatively connected to the shaft 23, is provided 15 so that either the pinion 24 or the pinion 25 may be placed in operative engagement with the bevel gear wheel 26, so that the vertical shaft 23 may be turned in either 20 direction, as desired.

In structures of this kind, it is desirable to elevate the reel for the purpose of placing or examining the skeins or hanks of yarn or other fibers carried thereby, and 25 since it may also be desirable to rotate the reel at any stage during the raising and the lowering of the same, the rotating mechanism is carried up and down by the lifting mechanism, the spline of the gear wheel 22 following the key-way in the vertical shaft 30 23. The mechanism for raising and lowering the reel may be as follows:

Suitably secured to base portions 31 and 32 of the side walls 1 of my improved structure, are vertically disposed screw rods 33 and 34, disposed in fixed relation and passing through arms 16^b and 17^b of the bearing brackets 16 and 17. These arms 16^b, 40 and 17^b carry bevel gear wheels 35 and 36, fixed thereto against vertical movement and having hubs 35^a and 36^a, with threaded bores 45 adapted to said screw rods and constituting nuts. As may be understood, if rotative motion is imparted to said bevel gear wheels 35 and 36, they will move on the threads of the fixed screw rods 33 and 34, and the brackets 16 carrying said gear wheels will 50 be raised or lowered, as desired, depending upon the direction of movement imparted to said gear wheels 35 and 36.

Passing through the hollow trunnions of the end spiders of the reel is a shaft 38, carrying at each end a bevel gear wheel indicated at 39 and 40, respectively, and these 55 bevel gear wheels are in operative engagement at all times with the gear wheels 35 and 36, whose threaded hubs 35^a and 36^a are carried by the bracket arms 16^b and 17^b adapted to the fixed screw rods 33 and 34.

In order that the motion of the gear wheel 21, which is driven by the gear wheel 22 of the vertical shaft 23, may be employed to rotate the reel or impart vertical movement thereto, I provide a clutch sleeve 41, 60 65 slideable on the shaft 38, which clutch sleeve

is in splined engagement with the hub of said gear wheel 21. The ends of this clutch sleeve are provided with suitable teeth for engagement with teeth at the end of the trunnion 8, which is free to turn in said hub until engaged by the clutch sleeve, or for engagement with teeth carried by the bevel gear wheel 40, which meshes with the bevel gear wheel 36. The clutch sleeve 41 is shown in Fig. 1, in the mid position.

When the parts are operatively engaged upon moving the sleeve 41 to the left, rotation of the helical gear wheel 21, by the helical gear wheel 22, will effect rotation of the trunnion 8 and with it the reel. When, however, the parts are operatively engaged upon moving the sleeve 41 to the right, rotation of the helical gear wheel 21 by the helical gear wheel 22, will effect rotation of the bevel gear wheel 40, and the consequent rotation of the shaft 38 and the bevel gear wheel 39; said gear wheels 39 and 40 in turn rotating the gear wheels 35 and 36 having the threaded hubs 35^a and 36^a, adapted to the fixed screw rods 33 and 34, and this motion will effect vertical movement of the bearing brackets 16 and 17, raising or lowering the reel.

It will be understood, therefore, that when the vertical shaft 23 is in action, with the clutch sleeve 41 in operative engagement with the trunnion 8, that the reel will be rotated within the bath of liquid contained in the tank or vat, and that when said clutch sleeve 41 is in operative engagement with the bevel gear wheel 40, the reel will be gradually raised or lowered, depending upon the direction of movement imparted to said vertical shaft 23.

I preferably interpose ball bearings 43 between the shaft 38 and the hollow trunnions 7 and 8 of the reel when ball bearings are employed between said trunnions and the brackets 16 and 17. In some instances, however, these collars may be dispensed with and plain bearings 43^b of the bushed type, such as illustrated in Fig. 6, may be employed.

The reel which I employ may be of any usual type common in the art, provided with suitable sticks 11 and 12 to receive the hanks or skeins of yarn, and the sticks 11 at the peripheral portion of said reel being journaled therein may be provided with means for imparting movement thereto, such as the star wheels 11^a, which may be arranged to contact with turning means as the reel is rotated so that the hanks or skeins of yarn or other fibers may be moved with respect to their supports to avoid stick marks on the same.

I claim:

1. In fiber-treating apparatus, the combination of a tank, a reel rotatably mounted in said tank, supporting members for said reel

- slidably mounted in the walls of said tank, means for raising and lowering said supporting members, gearing for rotating the reel in opposite directions; said gearing for 5 rotating the reel being in operative relation at all times so that said reel may be rotated when disposed in any position vertically of the tank, and means for driving said gearing.
- 10 2. In a fiber-treating apparatus, the combination of a tank having slotted side walls, a reel rotatably mounted in said tank, supporting members for said reel slidably mounted in said slotted side walls, gearing for 15 rotating the reel in opposite directions; said gearing for rotating the reel being in operative relation at all times so that said reel may be rotated when disposed in any position vertically of the tank, independent 20 gearing for raising and lowering the reel, and means for driving said gearing from a single source of power.
- 25 3. In a fiber-treating apparatus, the combination of a tank, a reel rotatably mounted in said tank, supporting members in which the reel is journaled slidably mounted in the walls of said tank, means for raising and lowering said supporting members, gearing for 30 rotating the reel in opposite directions; said gearing for rotating the reel being in operative relation at all times so that said reel may be rotated when disposed in any position vertically of the tank, and independent 35 gearing for raising and lowering the reel.
- 40 4. In fiber-treating apparatus, the combination of a tank having slotted side walls, a reel rotatably mounted in said tank, supporting members in which the reel is journaled slidably mounted in said slotted side walls, gearing for rotating the reel in opposite directions; said gearing for rotating the reel being in operative relation at all times so that said reel may be rotated when disposed in any position vertically of the tank, and independent 45 gearing for raising and lowering the reel.
- 50 5. In a machine for dyeing or treating yarn or other fibers, the combination of a tank having slotted sides, brackets adapted to move in said slotted sides, a reel journaled in said brackets, gearing for rotating said reel; said gearing for rotating the reel being in operative relation at all times so that said reel may be rotated when disposed in any position vertically of the tank, and independent 55 gearing for raising and lowering said reel-supporting brackets; such independent gearing comprising fixed screw rods disposed externally of the tank, bevel gears having hubs journaled in said brackets and threaded on said rods, and driving gears meshing with said bevel gears; and means for 60 independently driving the respective sets of gears.
- 65 6. In a fiber-treating apparatus, the combination of a tank having slotted sides, brackets adapted to move in said slotted sides, a reel journaled in said brackets, gearing for rotating said reel; said gearing for rotating the reel being in operative relation at all times so that said reel may be rotated when disposed in any position vertically of the tank, independent 70 gearing for raising and lowering said reel-supporting brackets; such independent gearing comprising fixed screw rods disposed externally of the tank, bevel gears having hubs journaled in said brackets and threaded on said rods, and driving gears meshing with said bevel gears; and means for independently driving the respective sets of gears.
- 75 7. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, a vertical shaft, helical gearing operatively connected between said vertical shaft and one of said trunnions, and means for driving said gearing to rotate said reel.
- 80 8. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, ball bearings interposed between said trunnions and brackets, a vertical shaft, helical gearing operatively connected between said vertical shaft and one of said trunnions, and means for driving said gearing to rotate said reel.
- 85 9. In a structure such as set forth in claim 7, a shaft centrally disposed with respect to said reel, bevel gears at the ends of said shaft, bevel gears carried by the brackets and moving therewith; said second set of bevel gears meshing with the gears carried by the shaft and having internally threaded hubs, fixed screw rods disposed for engagement with said threaded hubs, whereby movement of the bevel gears carried by said threaded hubs will effect vertical movement of the brackets and with them the reel, and means for rotating said shaft.
- 90 10. In a structure such as set forth in claim 7, a shaft centrally disposed in respect to said reel, anti-friction bearings between said shaft and the trunnions of said reel spiders, bevel gears at the ends of said shaft, bevel gears carried by the brackets and moving therewith; said second set of bevel gears meshing with the gears carried by the shaft and having internally threaded hubs, fixed screw rods disposed for engagement with said threaded hubs whereby movement of the bevel gears carried by said threaded hubs will effect vertical movement of the brackets and with them the reel, and means for rotating said shaft.
- 95 11. In a machine for dyeing or treating yarn or other fibers, the combination of a tank having slotted sides, brackets adapted to move in said slotted sides, a reel journaled in said brackets, gearing for rotating said reel; said gearing for rotating the reel being in operative relation at all times so that said reel may be rotated when disposed in any position vertically of the tank, independent gearing for raising and lowering said reel-supporting brackets; such independent gearing comprising fixed screw rods disposed externally of the tank, bevel gears having hubs journaled in said brackets and threaded on said rods, and driving gears meshing with said bevel gears; and means for independently driving the respective sets of gears.
- 100 12. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, ball bearings interposed between said trunnions and brackets, a vertical shaft, helical gearing operatively connected between said vertical shaft and one of said trunnions, and means for driving said gearing to rotate said reel.
- 105 13. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, ball bearings interposed between said trunnions and brackets, a vertical shaft, helical gearing operatively connected between said vertical shaft and one of said trunnions, and means for driving said gearing to rotate said reel.
- 110 14. In a structure such as set forth in claim 7, a shaft centrally disposed with respect to said reel, bevel gears at the ends of said shaft, bevel gears carried by the brackets and moving therewith; said second set of bevel gears meshing with the gears carried by the shaft and having internally threaded hubs, fixed screw rods disposed for engagement with said threaded hubs, whereby movement of the bevel gears carried by said threaded hubs will effect vertical movement of the brackets and with them the reel, and means for rotating said shaft.
- 115 15. In a structure such as set forth in claim 7, a shaft centrally disposed in respect to said reel, anti-friction bearings between said shaft and the trunnions of said reel spiders, bevel gears at the ends of said shaft, bevel gears carried by the brackets and moving therewith; said second set of bevel gears meshing with the gears carried by the shaft and having internally threaded hubs, fixed screw rods disposed for engagement with said threaded hubs whereby movement of the bevel gears carried by said threaded hubs will effect vertical movement of the brackets and with them the reel, and means for rotating said shaft.
- 120 16. In a machine for dyeing or treating yarn or other fibers, the combination of a tank having slotted sides, brackets adapted to move in said slotted sides, a reel journaled in said brackets, gearing for rotating said reel; said gearing for rotating the reel being in operative relation at all times so that said reel may be rotated when disposed in any position vertically of the tank, independent gearing for raising and lowering said reel-supporting brackets; such independent gearing comprising fixed screw rods disposed externally of the tank, bevel gears having hubs journaled in said brackets and threaded on said rods, and driving gears meshing with said bevel gears; and means for independently driving the respective sets of gears.
- 125 17. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, ball bearings interposed between said trunnions and brackets, a vertical shaft, helical gearing operatively connected between said vertical shaft and one of said trunnions, and means for driving said gearing to rotate said reel.
- 130 18. In a machine for dyeing or treating yarn or other fibers, the combination of a tank having slotted side walls, a reel comprising a plurality of spiders rotatably mounted in said tank, the end spiders of said reel having trunnions, sliding brackets in which said trunnions are journaled adapted to said slots, ball bearings interposed between said trunnions and brackets, a vertical shaft, helical gearing operatively connected between said vertical shaft and one of said trunnions, and means for driving said gearing to rotate said reel.

threaded hubs will effect vertical movement of the brackets and with them the reel, and means for rotating said shaft.

11. In fiber-treating apparatus, the combination of a tank having slotted side walls, a reel rotatably mounted in said tank, bearings for said reel slidably mounted in said slots, gearing for raising and lowering the reel including fixed screw-threaded rods engaged by a portion of said gearing, and means for driving said gearings.

12. In fiber-treating apparatus, the combination of a tank having slotted side walls, a reel rotatably mounted in said tank, bearings for said reel slidably mounted in said slotted side walls, a vertical shaft, a gear wheel carried by and operatively connectible with the reel, a gear wheel arranged to move on the vertical shaft and in operative engagement with the gear wheel carried by the reel, and means for rotating said vertical shaft.

13. In fiber-treating apparatus, the combination of a tank having slotted side walls, a reel rotatably mounted in said tank, trunnions for said reel, brackets slidably mounted in said slotted side walls in which said trunnions are journaled, a gear wheel carried by one of said trunnions, a clutch for placing said parts in operative relation, a vertical shaft, a gear wheel supported by one of the brackets and splined to said vertical shaft; said gear wheels being in operative engagement, and means for rotating said vertical shaft.

14. In fiber-treating apparatus, the combination of a tank having slotted side walls, a reel rotatably mounted in said tank and having hollow trunnions at its ends, bearings in which said trunnions are mounted, supports for said bearings slidably mounted in said slots, a shaft passing through said hollow trunnions, bearings for said shaft interposed between the same and the hollow trunnions, bevel gear wheels at the ends of said shaft, fixed screw rods disposed adjacent the sides of the tank, bevel pinions being threaded on said rods and operatively connected to said slideable bearing supports, and means for driving said shaft.

15. In fiber-treating apparatus, the combination of a tank having slotted side walls, a fiber-carrying reel rotatably mounted in said tank and having hollow trunnions at its ends, bearings in which said trunnions are mounted, supports for said bearings slidably mounted in said slots, a shaft passing through said hollow trunnions, bearings for said shaft interposed between the same and the hollow trunnions, bevel gear wheels at the ends of said shaft, fixed screw rods disposed adjacent the sides of the tank, bevel pinions in operative engagement with said gear wheels; said pinions being threaded on said rods and operatively connected to said

slideable bearing supports, driving means, and a clutch sleeve operatively disposed between said driving means and said shaft.

16. In fiber-treating apparatus, the combination of a tank having slotted side walls, a fiber-carrying reel rotatably mounted in said tank and having hollow trunnions at its ends, anti-friction bearings in which said trunnions are mounted, supports for said bearings slidably mounted in said slots, a horizontal shaft passing through said hollow trunnions, antifriction bearings for said shaft interposed between the same and the hollow trunnions, bevel gear wheels at the ends of said shaft, fixed screw rods disposed adjacent the sides of the tank, bevel pinions engaging said gear wheels; said pinions being threaded on said rods and operatively connected to said slideable bearing supports, a vertical shaft, a helical gear carried thereby, a helical gear meshing therewith carried by the reel, a clutch for placing reel and vertical shaft in operative engagement through said helical gearing, and means for driving said vertical shaft.

17. In a machine for dyeing or treating yarn or other fibers, the combination of a tank having slotted side walls, a reel for carrying said yarn comprising a plurality of spiders with cross rods connecting the same rotatably mounted in said tank; the end spiders of said reel having hollow trunnions, brackets in which said trunnions are journaled adapted to slide in the slotted walls of the tank, ball bearings interposed between said trunnions and the brackets, a vertical shaft, a helical gear carried by said vertical shaft, a helical gear in engagement therewith journaled on one of said trunnions, and clutching means for operatively connecting said gear and trunnion whereby movement imparted to the vertical shaft will rotate the reel.

18. In a machine for dyeing or treating yarn or other fibers, the combination of a tank having slotted side walls, a reel for carrying said yarn comprising a plurality of spiders with cross rods connecting the same rotatably mounted in said tank; the end spiders having hollow trunnions, brackets in which said trunnions are journaled supported by the side walls of said tank, ball bearings interposed between said trunnions and the brackets, a vertical shaft, a helical gear carried by said vertical shaft, a helical gear in engagement therewith journaled on one of said trunnions, and releasable means for operatively connecting one of said gears and the trunnion whereby movement imparted to the vertical shaft will rotate the reel.

19. In a machine for dyeing or treating yarn or other fibers, the combination of a tank having slotted side walls, a reel for carrying said yarn comprising a plurality

- of spiders with cross rods connecting the same rotatably mounted in said tank; the end spiders having hollow trunnions, brackets in which said trunnions are journaled 5 supported by the side walls of the tank, ball bearings interposed between said trunnions and the brackets, a vertical shaft, a gear wheel carried by said vertical shaft, a gear in engagement therewith loosely mounted on 10 one of said trunnions, a horizontal shaft extending through said reel, clutching means slidable on said horizontal shaft for operatively connecting one of said gears and the trunnion whereby movement imparted to the 15 vertical shaft will rotate the reel, and means for rotating said vertical shaft.
20. In a machine for dyeing or treating yarn or other fibers, the combination of a tank having slotted side walls, a reel comprising a plurality of spiders with cross rods connecting the same rotatably mounted in said tank; the end spiders having hollow trunnions, brackets in which said trunnions are journaled adapted to slide in said slots, 25 ball bearings interposed between said trunnions and the brackets, a horizontal shaft centrally disposed with respect to said reel, anti-friction bearings between said shaft and the trunnions of said reel, bevel gears at the 30 ends of said shaft, bevel gears carried by the brackets and movable therewith, said second set of bevel gears having internally threaded hubs, fixed screw rods disposed for engagement with said threaded hubs whereby movement of the bevel gears carried by said threaded hubs will effect vertical movement of the brackets and with them the reel, and means for driving said horizontal shaft. 35
22. In a machine for dyeing or treating yarn or other fibers, the combination of a tank having slotted side walls, a reel comprising a plurality of spiders with cross rods connecting the same rotatably mounted in said tank; the end spiders having hollow trunnions, brackets in which said trunnions are journaled adapted to slide in said slots, ball bearings interposed between said trunnions and the brackets, a horizontal shaft 40 axially disposed with respect to said reel, anti-friction bearings between said shaft and the trunnions of said reel, bevel gears at the ends of said shaft, bevel gears carried by the brackets and moving therewith, said second set of bevel gears having internally threaded hubs, fixed screw rods disposed for engagement with said threaded hubs whereby movement of the bevel gears carried by said threaded hubs will effect vertical movement of the brackets and with them the reel, a vertical shaft, a helical gear splined to said shaft, a helical gear meshing therewith and loose on one of the trunnions, a clutch for connecting said latter helical gear with the horizontal shaft, and means rotating said vertical shaft in either direction. 45
21. In a machine for dyeing or treating yarn or other fibers, the combination of a tank having slotted side walls, a reel comprising a plurality of spiders with cross rods connecting the same rotatably mounted in said tank; the end spiders having hollow trunnions, brackets in which said trunnions 50 are journaled adapted to slide in said slots, ball bearings interposed between said trunnions and the brackets, a horizontal shaft axially disposed with respect to said reel, anti-friction bearings between said shaft and the trunnions of said reel, bevel gears at the ends of said shaft, bevel gears carried by the brackets and moving therewith, said second set of bevel gears having internally threaded hubs, fixed screw rods disposed for engagement with said threaded hubs whereby movement of the bevel gears carried by said threaded hubs will effect vertical movement of the brackets and with them the reel, and means for driving said horizontal shaft. 55
23. In a machine for dyeing or treating yarn or other fibers, the combination of a tank having slotted side walls, a reel comprising a plurality of spiders with cross rods connecting the same rotatably mounted in said tank; the end spiders having hollow trunnions, brackets in which said trunnions are journaled adapted to slide in said slots, ball bearings interposed between said trunnions and the brackets, a horizontal shaft 60 axially disposed with respect to said reel, anti-friction bearings between said shaft and the trunnions of said reel, bevel gears at the ends of said shaft, bevel gears carried by the brackets and moving therewith, said second set of bevel gears having internally threaded hubs, fixed screw rods disposed for engagement with said threaded hubs whereby movement of the bevel gears carried by said threaded hubs will effect vertical movement of the brackets and with them the reel, and means for driving said horizontal shaft. 65
24. In a machine for dyeing or treating yarn or other fibers, the combination of a tank having slotted side walls, a reel comprising a plurality of spiders with cross rods connecting the same rotatably mounted in said tank; the end spiders having hollow trunnions, brackets in which said trunnions are journaled adapted to slide in said slots, ball bearings interposed between said trunnions and the brackets, a horizontal shaft 70 axially disposed with respect to said reel, anti-friction bearings between said shaft and the trunnions of said reel, bevel gears at the ends of said shaft, bevel gears carried by the brackets and moving therewith, said second set of bevel gears having internally threaded hubs, fixed screw rods disposed for engagement with said threaded hubs whereby movement of the bevel gears carried by said threaded hubs will effect vertical movement of the brackets and with them the reel, a vertical shaft, a helical gear splined to said shaft, a helical gear meshing therewith and loose on one of the trunnions, a clutch for connecting said latter helical gear with the horizontal shaft, and means rotating said vertical shaft in either direction. 75
25. In witness whereof I have signed this specification.

HOWARD M. DUDLEY.
